UNITED STATES PATENT OFFICE.

CHARLES E. PIERCE, OF CAMBRIDGEPORT, MASSACHUSETTS.

CRACKER-CAN.

SPECIFICATION forming part of Letters Patent No. 316,480, dated April 28, 1885.

Application filed April 26, 1884. (No model.)

To all whom it may concern:

Be it known that I, CHARLES E. PIERCE, of Cambridgeport, in the county of Middlesex and State of Massachusetts, have invented certain Improvements in Cracker-Cans, of which the following is a specification.

This invention has for its object to improve the construction of rectangular sheet-metal cans or boxes used mainly for holding crackers or like articles of food, and having a glazed opening in one side to display the contents of the can.

It is usual to provide the interior of the box with a movable partition placed near the glazed opening and adapted to hold a few of the crackers or other articles against the glazed front, so that the box will appear to be full whether its main receptacle is full or not.

The invention consists in the several improvements which I will now proceed to describe and claim.

Of the accompanying drawings, forming a part of this specification, Figure 1 represents a perspective view, front elevation, of a can provided with my improvements. Fig. 2 represents a section on line *x x*, Fig. 3. Fig. 3 represents a section on line *y y*, Fig. 2.

In carrying out my invention I construct a rectangular can by uniting together four side pieces, *s*, and a bottom piece, *b*, of sheet metal, the edges of said pieces being preferably connected by double-seaming, in the manner usually practiced in the manufacture of square or rectangular cans. One of the rectangular side pieces is provided with an aperture and is bent inwardly to form a beveled inwardly-projecting flange or margin, *m*, around said aperture, the portion of the piece surrounding said aperture being flat, as shown.

l represents a sheet or light of glass, which is placed within the can and bears against the inner edge of the beveled flange *m*, and is held in contact therewith by a lug or flange, *n*, secured to the bottom of the can, and a flange, *o*, formed by bending downwardly the upper edge of the side piece, *s*, in which the opening is formed. Said flanges *n* and *o* are adapted to bear with a sufficient degree of pressure to prevent the glass from rattling and to press it closely against the beveled flange *m*.

In inserting the glass its upper edge is first placed behind the flange *o*, and then it is pushed

upwardly until its lower edge can pass over the flange *n*, and then dropped until its lower edge rests on the bottom of the can, the flange *o* being of considerable depth, so as to allow the described movements of the glass and bear against it after it is dropped to place behind the flange *n*.

Heretofore it has been usual to solder a marginal glass holder or frame to the body of the can, one of the sides of the can being left open and the adjoining sides being turned inwardly to form flanges to support the rear side of the glass, a space being left for the glass between said flanges and the soldered-on portion, the latter bearing against the front side of the glass. Said construction involves the employment of several pieces, and is not strong and durable, owing to the liability of the soldered joints to give way at the corners of the can. The glass is moreover held close to the front surface of the can, so that it is liable to be broken.

By my improved construction one of the side pieces of the can united to the adjacent pieces in the ordinary manner is enabled to hold the glass by the aid only of the lug or flange *n*, secured to the bottom of the can.

No parts are required to be soldered to the can, excepting said flange *n*, which may be otherwise secured, if preferred.

The beveled flange *m* around the aperture not only gives the can a neat and pleasing effect, but also keeps the glass back from the front surface of the can, so that it is less liable to breakage than heretofore. The flange also stiffens the side piece, so that it is not so liable to be bent and distorted as an ordinary side piece, the flange affording a stiff bearing for the glass, not liable to be warped or bent, so as to form dust-admitting crevices between it and the glass.

I do not limit myself to the application of the apertured side piece to the adjacent sides of the can by double-seaming, as said piece may be soldered to the adjacent pieces, if desired.

p represents the partition, which is placed within the box near the light of glass and subdivides the interior of the box into two parts, the one between the partition and the glazed side being narrow and adapted to hold a layer or a small quantity of crackers, while the other

constitutes the receptacle from which the crackers are taken as required. Said partition therefore holds a small quantity of the goods against the glass, so that the can will always appear full when viewed from the glazed side. Heretofore the partition has been adapted to slide in and out of the box between edge-guides secured to the sides of the box, the partition being removed while the display-crackers are being arranged on the glass and then pushed in. It is difficult, however, with this arrangement to insert the partition without injuring or displacing the crackers by the edge of the partition, said edge cutting or moving the crackers unless they are very carefully arranged to avoid contact with the partition. I obviate this difficulty by hinging the partition at one edge to the box at *q*, and providing a hook or fastening device, *r*, for the other edge, as shown in Figs. 2 and 3. The operator is thus enabled to arrange the crackers and then confine them by swinging the cover toward the glazed opening,

the elasticity of the cover enabling it to bend and conform to the arrangement of the 25 crackers.

I claim—

1. A rectangular sheet-metal can or box having an internal glass-holding flange, *n*, and an apertured side piece bent inwardly around its aperture to form a beveled flange, *m*, and bent downwardly at its upper edge to form a glass-holding flange, *o*, as set forth. 30

2. A sheet-metal can or box having an apertured and glazed side piece, an internal partition hinged at one edge to the box, and a fastening device for the swinging edge of said partition, as set forth. 35

In testimony whereof I have signed my name to this specification, in the presence of two 40 subscribing witnesses, this 19th day of April, 1884.

CHARLES E. PIERCE.
